(57) **CLAIM**

The ornamental design for an elastic member of an elastic coupler, as shown and described.

DESCRIPTION

FIG. 1 is a perspective view of an elastic member showing our new design;

FIG. 2 is a front view thereof;

FIG. 3 is a right side view thereof, a left side view being a mirror image thereof;

FIG. 4 is a top view thereof, a bottom view being a mirror image thereof;

FIG. 5 is a back view thereof; and,

FIG. 6 is a cross-sectional view thereof taken along the line VI—VI in FIG. 2.
